(57) **CLAIM**

The ornamental design for a rotating laser, as shown and described.

DESCRIPTION

The file of this patent contains at least one drawing executed in color. Copies of this patent with color drawings will be provided by the Office upon request and payment of the necessary fee.

FIG. 1 is a front perspective view of a rotating laser, showing our new design.

FIG. 2 is a rear perspective view of the rotating laser of FIG. 1.

FIG. 3 is a front elevational view of the rotating laser of FIG. 1.

FIG. 4 is a rear elevational view of the rotating laser of FIG. 1.

FIG. 5 is a left side view of the rotating laser of FIG. 1.

FIG. 6 is a right side view of the rotating laser of FIG. 1.

FIG. 7 is a top plan view of the rotating laser of FIG. 1; and, FIG. 8 is a bottom plan view of the rotating laser of FIG. 1.
